CLAIM

The ornamental design for a tree lamp, as shown and described.

DESCRIPTION

FIG. 1 is a top perspective view of a tree lamp showing my new design;

FIG. 2 is a bottom perspective view of the tree lamp therefore;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion “9” in FIG. 1;

FIG. 10 is an enlarged view of the selected portion “10” in FIG. 2;

FIG. 11 is an enlarged view of the selected portion “11” in FIG. 3; and,

FIG. 12 is an enlarged view of the selected portion “12” in FIG. 4.

Any shading and cross-hatching are not features of the design but are utilized to illustrate the surface contours of the tree lamp design in the drawings. The dash-dot-dash broken lines define the boundary of the enlarged views and form no part of the claimed design.
